TIP-UP FOR ICE FISHING

Karl G. T. Happe, 38 Tara Ave.,
Scarborough, Ontario, Canada

Filed Oct. 2, 1969, Ser. No. 19,382

Term of patent 14 years

Int. Cl. D22—08

U.S. Cl. D22—22

FIG. 1 is a perspective view of a tip-up for ice fishing showing my new design;

FIG. 2 is an end elevation of the tip-up shown in FIG. 1; and

FIGS. 3 to 5 are sections taken along lines 3—3, 4—4 and 5—5 respectively in FIG. 1; and

FIG. 6 is a top elevation of the tip-up shown in FIG. 1.

I claim:

The ornamental design for a tip-up for ice fishing, as shown.
